UNITED STATES PATENT OFFICE.

CARL HALLAUER, OF BRAWLEY, CALIFORNIA.

CHARGE-FORMING DEVICE.

Application filed July 23, 1923. Serial No. 653,229.

To all whom it may concern:

Be it known that I, CARL HALLAUER, a citizen of the United States, residing at Brawley, in the county of Imperial and 5 State of California, have invented new and useful Improvements in Charge-Forming Devices, of which the following is a specification.

This invention relates to a device for 10 forming an explosive charge for internal combustion engines.

An object of the invention is to provide a means for regulating the feed of a mixture of fluid hydrocarbon fuel, air and 15 water vapors, to the intake of an engine.

Another object is to provide a device of the above character which is so constructed that it may be readily operated to vary the 20 relative proportions of fuel and water vapors according to variations in engine speed, and which embodies means whereby volumes of air at different temperatures may be delivered to a mixing chamber together with the fuel and water vapors in accordance with the engine requirements.

A further object is to provide an attachment for internal combustion engines which is particularly adapted for use on the engines of tractors and similar heavy duty 30 vehicles in which low grade fuels are employed whereby the fuel is rendered quite thoroughly combustible and at the same time detonating explosion thereof in the engine be obviated thereby effecting a uniform 35 gradual application of the expansive power of the exploded fuel on the engine pistons.

With the foregoing objects in view, together with such other objects and advantages as may subsequently appear, my 40 invention resides in the parts and construction hereinafter described, claimed and illustrated in the accompanying drawings, in which:—

Figure 1 is a perspective view showing 45 the application of the invention.

Fig. 2 is a view in longitudinal section of the regulating valve and its connections as seen on line 2—2 of Fig. 3.

Fig. 3 is a view in transverse section of 50 the regulating valve and its connections as seen on the line 3—3 of Fig. 2.

Fig. 4 is a view in cross section of the regulating valve showing it as disposed in the starting and idling position.

Fig. 5 is a diagram of the regulation 55 valve as extended on a plane to show the

relative positions of the parts as disposed in Fig. 4.

Fig. 6 is a sectional view of the valve showing it in a slightly advanced position 60 from that shown in Fig. 4 as when the engine is operated under a light load.

Fig. 7 is a diagrammatic view of the valve in the position shown in Fig. 6.

Fig. 8 is a sectional view showing the 65 valve as disposed in approximately an intermediate position as when the engine is operating under a moderate load.

Fig. 9 is a diagrammatic view of the valve in the position shown in Fig. 8. 70

Fig. 10 is a sectional view of the valve showing it in its fully open position as when the engine is operating under full load.

Referring to the drawings more specifically, 11 indicates an internal combustion engine fitted with an exhaust manifold 12 and an intake manifold 13. In carrying out my invention I provide a multiple regulating valve 14 for controlling the feed of 80 air and vapors from a pair of carburetors 15 and 16; the valve being located between the carburetors and the intake manifold, and serving as a throttle. The regulating valve is also adapted to control the delivery 85 of warm air to the air and vapors delivered from the carburetors as will be hereinafter described.

The regulating valve 14 embodies a casting 17 in which is turnably mounted a 90 tapered sleeve valve member 18, which valve member is hollow and is open at its reduced end. The enlarged end of the valve member 18 is provided with an end wall 19 to which is attached a stem 20 95 fitted with a lever 21; the stem extending through a bearing 22 on a cap 23 screwed on the valve casing 17. A coil spring 24 is wound around the stem 20 and bears between the bearing 22 and the wall 19 of the 100 valve member and serves to maintain the valve member in a closely seated position in the valve casing.

Extending through the end of the valve casing and projecting into the chamber 25 105 interiorly of the valve member 18 is a nozzle 26, leading from the discharge passage 27 of the carburetor 15. The nozzle 26 is formed with an end wall 28 adjacent which are side discharge openings 29 which 110 open to the valve chamber 25.

The carburetor 15 may be of any suitable

construction being provided with an air intake 30, a float chamber 31, a mixing chamber 32 and a needle valve 33 for regulating the flow of fuel from the float chamber to the mixing chamber 32. A fuel feed pipe 34 communicated with the float chamber 31 leads from any suitable source of fuel supply; there being the usual float controlled feed valve (not shown) controlled by a float 35 in the float chamber. Communicating with the air intake 30 of the carburetor 15 is a hot air feed pipe 36 which connects with a duct interiorly and extending longitudinally of the exhaust manifold 12; the duct 37 opening at its outer end through an air intake opening 38 formed in the exhaust manifold. It will be seen that a direct communication is afforded between the air-intake 38 and the mixing chamber 25 in the multiple valve 14 through the duct 37, pipe 26, carburetor inlet 30, carburetor mixing chamber 32, carburetor outlet 27, and nozzle 26. The duct 37 has walls 39 interiorly of the exhaust manifold which will become highly heated on the passage of hot gases through the exhaust manifold so that air passing through the duct 37 will be highly heated and whereby hot air may be delivered to the fuel carburetor 15 and to the mixing chamber 25 in the regulating valve 14.

The valve casing 17 is formed on its under side with an outlet 40, which communicates with the intake manifold 13 and is formed in its upper wall portion with a warm air inlet opening 41 with which communicates a pipe 42, the outer end of which opens to a heating chamber 43 formed by a wall 44 extending over the exhaust manifold 12; the wall 44 being here shown as formed integral with the exhaust manifold and extending longitudinally thereof with air intake openings 45 at its ends.

The valve member 18 is formed with an outlet port 46 adapted to afford communication between the chamber 25 and the outlet 40 and to vary the area of the communication on turning the valve as will be later described. The valve is also formed with an intake port 47 adapted to be moved in or out of register with the air inlet opening 41 to open or close communication between said inlet and the chamber 25, and to regulate the area of the inlet on turning valve member 18.

The pipe 42 is fitted with a choke valve 48 here shown as of the butterfly type by means of which the passage through the pipe 42 may be closed to cut off the air feed to the inlet opening 41.

The valve casing 17 is formed in the side wall portion thereof with a cold air inlet opening 49 which communicates with the outlet 50 of the carburetor 16, which carburetor is provided with the usual air inlet

51 communicating with the mixing chamber 52 in the carburetor, and which carburetor also embodies a float chamber 53 with which connects a water feed pipe 54 leading from any suitable source of water supply being here shown as connected to the water jacket of the engine casing. There is a float operated valve (not shown) in the carburetor 16 for controlling the water feed thereto actuated by a float 55 in the float chamber 53 in the usual manner. A needle valve 56 is provided to regulate the feed of water from the float chamber 53 to the mixing chamber as is common in carburetor construction. The valve 18 is formed with a port 57 adapted to be moved in or out of register with the cold air inlet opening 49 to open or close the communication between the cold air inlet and the chamber 25, and to vary the area of said communication.

The ports 46, 47 and 57 in the valve member 18 are arranged circumferentially thereof in such relation to the outlet 40 and inlets 41 and 49 in the valve casing that when the warm air inlet 41 is fully opened by the port 47 as shown in Figs. 3 and 6 the cold air inlet opening 49 will be fully closed and the outlet 40 will be partly open; and when the valve member 18 is disposed in its fully retracted position the outlet 40 will be nearly closed, the warm air inlet 41 partly closed, and the cold air inlet 49 fully closed, as shown in Figs. 4 and 5. When the valve member 18 is disposed in an intermediate advanced position to close the warm air inlet 41 the cold air inlet will be partly open and the communication to the outlet 40 will be enlarged as shown in Figs. 8 and 9. When the valve is disposed in its fully advanced position the cold air inlet opening 49 and the outlet 40 will be wide open and the warm air inlet 41 will be closed as shown in Fig. 10.

In the operation of the invention, before starting the engine the valve 18 is turned to its retracted position as shown in Fig. 4 so as to close the water and air supply and restrict the valve outlet leading to the intake manifold, and the choke valve 48 is closed so that on starting the engine the suction induced thereby in the intake manifold will act solely to draw fuel and air from carburetor 15 through the feed pipe 26 which air, after a few explosions in the engine will become highly heated by the action of the hot exhaust gases passing through the exhaust manifold. The choke valve 48 is then opened which permits the addition of warm air to the mixture of hot air and vapors entering the valve chamber to render this mixture of air and fuel more lean.

When the engine is to be operated under a light load the volume of warm air may be increased which is effected by turning the valve so as to fully open the warm air inlet

and increase the extent of opening of the port 46. When the engine is to be operated under a moderate load the valve is turned to increase the opening of the port 46 and thereby increase the feed of the gases and vapors to the engine and at the same time open the port communicating with the water carburetor 16. When the engine is to be operated at full load the valve is turned to fully open the port controlling the feed to the engine, and also fully open the port communicating with the water carburetor.

It will be observed that the valve 18 serves as a throttle, as the feed to the engine is controlled by varying the opening of the port 46.

In order to effect a more rapid feed to the engine in putting it under moderate load, the port 46 is formed with an enlarged portion which, when the valve is turned to the position shown in Figs. 8 and 9, the opened port area will be rapidly increased.

By the arrangement of the ports in the valve relation to the openings in the valve casing as here set forth, the operation of the valve to accelerate or diminish the speed of the engine, the mixtures delivered to the engine will be automatically varied in their proportions and character relative to the engine speed, it being seen that when the valve is disposed in operating the engine, under a light load, a lean mixture of the fuel and air delivered to the engine will be effected, and on turning the valve to increase the engine speed, the mixture will become enriched by reason of the warm air intake being restricted, and the feed to the engine enlarged.

In order to obviate the detonation of the charge when the engine is operating under a heavy load water vapors are added by opening the communication to the carburetor 16.

While I have herein described a specific embodiment of my invention and the particular application thereof, I do not limit myself to the exact details of construction and arrangement shown, but may employ such changes and modifications as come within the scope of the appended claims.

I claim:

1. In a charge forming device, an intake manifold, a valve formed with a chamber having an outlet adapted on operation of the valve to effect variable communication with the intake manifold, said valve adapted to receive warm air, a mixture of cold air and water, a mixture of hot air and fuel from separate inlets leading to the valve chamber, said inlets and outlets being adapted on operation of said valve to effect variations in the proportions of the warm air, cold air and water mixture, and hot air and fuel mixture received by said chamber.

2. In a charge forming device, an intake manifold, a valve having a chamber and an

outlet adapted to communicate with said intake manifold, a carburetor, means for delivering a mixture of hot air and fuel from said carburetor to the chamber in the valve, a second carburetor, and means for delivering a mixture of cold air and water vapors from said second carburetor to the valve chamber.

3. In a charge forming device, an intake manifold, a valve having a chamber provided with an outlet adapted to communicate with said intake manifold, a carburetor, means for delivering a mixture of hot air and fuel vapors from said carburetor to the valve chamber, a second carburetor, means for delivering a mixture of cold air and water vapors from said second carburetor to the valve chamber, and separate means for delivering warm air to the chamber in the valve, said valve operable to cut off the warm air feed when the cold air and water mixture feed occurs.

4. In a charge forming device, an intake manifold, an exhaust manifold, a valve formed with a chamber having an outlet adapted to communicate with the intake manifold, a fuel carburetor having an intake and an outlet, said intake communicating with an air heating duct arranged in said exhaust manifold, a nozzle leading from the carburetor outlet to the chamber in the valve, a second carburetor having an outlet adapted to communicate with the chamber in the valve on operation of the latter and provided with an air inlet, and means for delivering water to said last named carburetor.

5. In a charge forming device, an intake manifold, an exhaust manifold, a valve formed with a chamber and having an outlet adapted to communicate with the intake manifold, a fuel carburetor having an intake and an outlet, said intake communicating with an air heating duct in said exhaust manifold, a nozzle leading from the carburetor outlet to the valve chamber, a second carburetor having an outlet adapted to communicate with the valve chamber on operation of the latter and provided with an air inlet, means for delivering water to said last named carburetor, and means controlled by said valve for delivering warm air to said chamber.

6. In a charge forming device, an intake manifold, a valve casing having an outlet communicating with said intake manifold, a tapered valve in said casing having a chamber therein formed with an outlet port adapted to open communication between said chamber and the outlet in the valve casing and to vary extent of the communication on rotation of the valve, means for delivering hot carbureted fuel vapors to the valve chamber, and means for delivering a mixture of air and water to said chamber.

7. In a charge forming device, an intake manifold, a valve casing having a discharge outlet communicating with said manifold, a hollow valve in said casing having an outlet port adapted to form a variable communication between the interior of said valve and the outlet in the valve casing, a fuel carburetor, a nozzle connecting with the discharge side of said carburetor arranged to discharge into the interior of said valve, a second carburetor communicating with sources of water and air supply, said second carburetor having an outlet controlled by said valve and said valve being adapted to control the flow of a mixture of air and water vapors to the interior thereof.

8. In a charge forming device, an intake manifold, a valve casing having a discharge outlet communicating with said manifold, a hollow valve in said casing having an outlet port adapted to form a variable communication between the interior of said

valve and the outlet in the valve casing, a fuel carburetor, a nozzle connecting with the discharge side of said carburetor arranged to discharge into the interior of said valve, a second carburetor communicating with sources of water and air supply, said second carburetor having an outlet controlled by said valve being adapted to control the flow of a mixture of air and water vapors to the interior thereof.

9. In a charge forming device, an intake manifold, a pair of carburetors one of which is adapted to receive liquid fuel and air and the other of which is adapted to receive water and air, a regulating valve interposed between the intake manifold and said pair of carburetors operable to regulate the delivery of fuel and air from one carburetor and water and air from the other, and means controlled by said valve for delivering warm air to the intake manifold.

CARL HALLAUER.
